UNITED STATES PATENT OFFICE.

MICHAEL GERVASIO, OF BUFFALO, NEW YORK.

RAILROAD SWITCH.

Application filed March 24, 1926. Serial No. 97,072.

The present invention relates to a shielding device for railroad switches and has for its principal object to provide a structure for protecting the switch from snow and the like, so that the switch may be efficiently operated at all times in a fairly reliable manner.

Another very important object of the invention is to provide a highly novel device of this nature which is simple in its construction, inexpensive to manufacture in comparison to the expenses incident to labor in keeping switches open at the present time, one which is durable and not likely to easily become out of order and otherwise well adapted to the purpose for which it is designed.

With the above and numerous other objects in view as will appear as the description proceeds, the invention resides in certain novel features of construction, and in the combination and arrangement of parts as will be hereinafter more fully described, and claimed.

25 In the drawings:—

Figure 1 is a top plan view of a railroad switch showing my shielding structure associated therewith.

Figure 2 is a transverse section there-
30 through taken substantially on the line 2—2 of Figure 1.

Figure 3 is a perspective view of one of the hinged shielding elements.

Figure 4 is a perspective view of one of the movable shielding elements.

Figure 5 is a perspective view of one of the fixed shielding elements.

Figure 6 is a detail view taken substan-
35 tially on the line 6—6 of Figure 1.

Figure 7 is a detail view of the arcuate slots.

Referring to the drawings in detail it will be seen that I have illustrated in the drawings a conventional form of railroad switch mounted in the usual well known manner on ties 5. For the purposes of this description I shall refer to the fixed outer rails of the switch by the numerals 6 and the inner movable rails by numerals 7. The 45 rails 7 are switched in the usual manner by an operating mechanism indicated generally by the numeral 8.

Shield plates 9 are fixed to the inner sides of the bases of the rails 7 to extend there-
50 between. The connections 10 between the bases of the rails 7 and shield plates 9 are

of a pin and slot type, the slot being slightly arcuate to accommodate the switching of these rails. The plates 9 are disposed with their ends in overlapping relation to one another as is apparent from Figures 1 and 2. The right hand edge of the right hand plate 9 in Figure 1 is preferably disposed downwardly to prevent the collection of snow under these plates 9. Shield elements 11 are disposed forwardly of the right hand plate 9 and forwardly of the free ends of the rails 7 and prevent snow from flowing or drifting between one of the rails 7 and one of the rails 6 when there is a space there-
55 between such as is shown in the lower portion of Figure 1. These shield elements 11 are illustrated to particular advantage in Figures 5 and 6 and have base portions 12 and raised portions 13. The base portions 60 12 are fixed to the adjacent ties by suitable fastening elements, the height of the shield element being such as to allow the flanges of the vehicle wheel to readily clear the same.

Shield plates 14 have their outer edges 65 fixed to the ties by suitable fastening elements and are bowed upwardly and inwardly under the outside of the heads of rails 6 as is more clearly illustrated in Figure 2.

In order to prevent the collection of snow 70 between rails 6 and 7, I utilize two movable shielding elements designated generally by the letters A and B. The elements B are substantially triangular in formation having a longitudinally disposed series of apertures 16 for receiving bolts 17 rising from the ties 5 between rails 6 and 7. Springs 18 are disposed on these bolts for holding the element B normally raised between the heads of the rails 6 and 7 as is shown in 75 Figure 2. The base ends of the elements B are located adjacent the pivots of the rails 7 as is shown to advantage in Figure 1, while the apices thereof terminate a distance from the free ends of said rails. 80 These elements B do not interfere in any way with the movement of the rails 7 and have one side thereof in close proximity to the rails 6. When a rail 7 moves away from the corresponding rail 6 a space is left 85 between the other side of the corresponding element B and the corresponding rail 7 as is illustrated in the lower portion of Figure 1. As is illustrated in the upper portion of Figure 1 the elements B are triangular 90 shaped to permit the rails 7 to be moved so that their free ends abut against the rails

95 100 105 110

6. The additional shield element A is supplementary to the shield elements B and are hinged to the rails 7. Each shield element A includes a body 20 and a right angularly disposed longitudinal flange 21. Hinge elements 22 are engaged with the flange 21 and with the rails 7. Some of the hinge elements 22 are engaged through the intermediacy of blocks 23 as the hinge elements 10 should have their pivots located immediately below the outer sides of the heads of the rails 7. The webs of the rails 7 are provided with arcuate openings 24 for receiving arcuate bolts 25 attached to the body 20. 15 Springs 26 are disposed on the arcuate bolts 25 to impinge against the bodies 20 and the webs of the rails 7 for normally holding the bodies 20 raised as is indicated to the right hand side of Figure 2 under the corresponding element B. Only a portion of the element overlaps the body 20. It will also be seen that when the switch is operated one of the elements A will be swung to the position shown to the left of Figure 2 while 25 the other element A will spring upwardly to the position to the right of Figure 2. The free edges of the body 20 are curved as is indicated at 28 for engaging the head of the adjacent rail 6 in order that the element A may be swung downwardly to an 30 out of the way position as the rail 7 approaches the rail 6.

It is thought that the construction, operation, utility and advantages of this invention will now be clearly understood by those skilled in this art without any more detailed description thereof. The present embodiment of the invention has been disclosed in detail merely by way of example since in 35 actual practice it attains the features of advantages enumerated as desirable in the statement of the invention and the above description. It will be apparent that numerous changes in the details of construction, 40 and in the combination and arrangement of parts may be resorted to without departing from the spirit or scope of the invention 45

as hereinafter claimed or sacrificing any of its advantages.

Having described my invention, what I 50 claim and desire to secure by Letters-Patent, is:—

1. A railroad switch shielding mechanism, wherein the switch includes a pair of outer fixed rails and a pair of inner movable rails, comprising shield elements fixed to the outside of the fixed rails, shield elements mounted between and fixed to the movable rails, and movable shield elements between the movable rails and the fixed 55 rails, one of said movable elements being provided with apertures, bolts rising through said apertures, and springs on the bolts holding said last-mentioned elements 60 normally raised.

2. A railroad switch shielding mechanism, wherein the switch includes a pair of outer fixed rails and a pair of inner movable rails, comprising shield elements fixed to the outside of the fixed rails, shield elements 70 mounted between and fixed to the movable rails, and movable shield elements between the movable rails and the fixed rails, one of said movable elements being provided with apertures, bolts rising through said apertures, 75 springs on the bolts holding said last-mentioned element normally raised, and the other of said elements hinged to the movable rails and springs associated therewith for normally holding said other element raised. 80

3. A shielding structure for railroad switches, wherein the switch includes a fixed rail and a movable rail, comprising a shield element hinged to the movable rail and having a free edge curved downwardly for engaging the fixed rail, arcuate bolts piercing the web of the movable rail and fixed to the shield element and springs on said bolts between the element and the web of the movable rail for normally holding the element 85 raised.

In testimony whereof I affix my signature.

MICHAEL GERVASIO.
